UNITED STATES PATENT OFFICE.

SAMUEL W. NESBITT, OF SPRINGFIELD, MASSACHUSETTS.

DEVICE FOR DRESSING GRINDING-WHEELS.

1,001,430.

Specification of Letters Patent. Patented Aug. 22, 1911.

Application filed April 16, 1910. Serial No. 555,958.

To all whom it may concern:

Be it known that I, SAMUEL W. NESBITT, a citizen of the United States of America, and resident of Springfield, in the county of 5 Hampden and State of Massachusetts, have invented certain new and useful Improvements in Devices for Dressing Grinding-Wheels, of which the following is a full, clear, and exact description.

10 The object of this invention is to produce a device for simultaneously dressing the working faces of opposed cup shaped grinding wheels.

In certain special machinery a pair of 15 grinding wheels are provided which are rotatable on arbors therefor which are axially coincident and which grinding wheels are movable, the one relatively to the other on the line of their common axis so that the 20 working faces of the cup shaped grinding wheels may simultaneously finish, by grinding, the opposite faces of any given piece of work, such, for instance, as a wrench bar forging.

25 In the carrying out of this invention a device is provided which consists of a holder and a pair of rotary grinding wheel dressing tools which are journaled for their free rotations on the holder and have their working portions extended and exposed beyond 30 opposite lateral portions of the holder, so that by the presentation of the head or working portion of the device between the grinding faces of a pair of cup shaped 35 grinding wheels and the positioning of the one wheel in suitable proximity to the other, both of the grinding faces of the wheels will be simultaneously dressed,—that is they will be freshened and rendered more 40 abrasive in their character after, from more or less protracted use, having become glazed and impaired for their most efficient surface grinding action.

The invention is described in conjunction 45 with the accompanying drawings and is defined in the claims.

In the drawings, Figure 1 is a plan view of the device for dressing grinding wheels,—a portion thereof at its forward end being 50 represented in horizontal section; Fig. 2 is an edge view of the device; Fig. 3 is a perspective view showing the detachable head for carrying the dressing tools and parts appurtenant to such head in separated relations.

Similar characters of reference indicate corresponding parts in all of the views.

The device will be described as the same has been specifically constructed and practically used, although it is to be understood 60 that various changes of a minor character may be made in the device without departing from the invention.

In the drawings A represents a stock comprising a substantially rectangular body 65 portion *a* and a handle portion *b*; and B represents a tool carrying head which is represented in the form of a block which at its rear is provided with a horizontal rib *d* which has an interlocking engagement in a 70 groove *f* therefor in the forward edge of the stock. The said head has opposite sidewise opening recesses *g* *g*, and socket holes *h* *h* arranged in parallelism on lines transversely of the recesses, these socket holes being 75 in the portions of the head both to the front and to the rear of the recesses, and open at the front edge of the head.

D represent studs on which the rotary dressing tools *x* *x* are journal-supported. 80 These studs are engaged through the socket holes, bottoming against the inner end of the latter and they pass through the perforated or apertured centers of the dressing tool, which latter may be constituted by al- 85 ternated disks and star shaped or radially bladed members as commonly comprised in already well known dressing tools for grinding wheels. The said studs have step shaped outer end portions whereby shoul- 90 ders at right angles to each other are produced as represented at *i* and *j*, the shoul- ders *i* being at right angles to the lengths of the studs while those *j* are along the lengths of the studs and located outside of the 95 shoulders *i*; and these step-shaped or shoul- dered ends of the studs receive engagements therewith of a single plate or flat bar F which is held in its confinement by a screw G the shank of which passes through said 100 plate and also through the head B and with a screw engagement into the stock and which screw by its head has a confining en- gagement against the plate to hold it im- movably in its position as shown. This 105 screw confined plate holds the journal studs against endwise displacement and the shoulders of the screw studs which engage the end edges of the plate in turn prevent the latter from having any rotative shifting 110

movement, while the screw serves the double duty of securing the plate on the head and confining the head on the stock.

By the means of detachable connection 5 shown and last above referred to, new or different sized dressing tools may be replaced in the head and a head of one width, or having dressing tools of a given operative nature may be substituted on the stock 10 for one of some other size or nature of equipment.

I am aware that a device for dressing emery wheels has been proposed having at the forward end of the handle or holder a 15 pair of dressing tools which are of dissimilar character, one being for rough dressing and the other for fine dressing, and both projecting as to working portions thereof beyond the end or head of the holder; but 20 such a device could not possibly be used for simultaneously dressing the grinding faces, each having the shape of an annulus, of two oppositely located cup shaped wheels, as represented at y and y' in Fig. 1 of the accompanying drawing. And somewhat further explaining the manner of utilization 25 of the present device, it will be understood that the grinding wheel y' is mounted for its rotation on a carriage which is bodily movable toward and away from the grinding wheel y . Now the stock is supported on a rest z so that its forward end having the tool carrying head is in presentation between the annular faces of the two cup 30 shaped grinding wheels, and the one y' is moved against the adjacent dressing tool and will be dressed thereby and by the contact of the grinding wheel y' against the tool the device will be bodily crowded 35 against the further grinding wheel's annular face to simultaneously effect the dressing of the latter. And it is to be particularly appreciated that it is of importance in the making of this device that the working portions of the dressing tools x protrude be-

yond opposite lateral portions of the holder therefor.

I claim:—

1. A device for simultaneously dressing the working faces of opposed cup-shaped 50 grinding-wheels, consisting of a holder, and a pair of rotary dressing tools journaled on the holder, and having their working portions extended beyond opposite lateral portions of the holder.

2. In a grinding wheel dressing device, the combination with a holder having recesses in the forward portion thereof which open to opposite lateral edge portions of the holder, of rotary dressing tools journal supported in said recesses, with their working portions protruding outwardly from said recesses and beyond the opposite lateral edges of the holder.

3. In a device for dressing grinding wheels, 65 in combination, a stock and a head having rib and groove engagements and said head having opposite sidewise opening recesses and socket holes arranged transversely of the recesses, rotary stone dressing tools located in 70 said recesses and having their working portions extending outwardly beyond the ends thereof, journal studs engaged in said socket holes and on which the rotary dressing tools are supported and which studs 75 have step shaped outer end portions, a plate which by its opposite ends engages the step shaped ends of said journal studs, and a screw the shank of which passes through said plate, said head and with a screw engagement into the stock, and which by its head 80 has a confining engagement against the plate.

Signed by me at Springfield, Mass., in presence of two subscribing witnesses.

SAMUEL W. NESBITT.
